[57] CLAIM

The ornamental design for a sofa for pets, as shown and described.

DESCRIPTION

FIG. 1 is a perspective view of a sofa for pets showing my new design, the broken lines are for purposes of illustration only and form no part of the claimed design;

FIG. 2 is a left side elevational view thereof, the right side is a mirror image;

FIG. 3 is a front elevational view thereof;

FIG. 4 is a rear elevational view thereof; and,

FIG. 5 is a top plan view thereof.

The bottom view is plain and unornamented.
